Application June 15, 1953, Serial No. 361,782

Claims priority, application Netherlands June 27, 1952

11 Claims. (Cl. 68—175)

The present invention relates to the treatment of threads and more particularly to a liquid aftertreatment of a sheet or warp of closely spaced parallel threads passing in a horizontal or substantially horizontal plane through an open receptacle filled with a suitable liquid. This invention represents a further development over that described and claimed in the copending Schrenk application Serial No. 292,920, filed June 11, 1952, now Patent No. 2,674,113, issued April 6, 1954, and assigned to the same assignee as the present application.

More particularly, this invention relates to a device for the continuous treatment with liquids of a number of closely spaced threads running in an almost horizontal plane, in which the threads are led along the undersides of guide rollers located at the beginning and end of a trough at a distance of some millimeters, e. g., 3-7 mm., below the liquid level therein.

It is well known that during the liquid bath treatment of a number of threads running in parallel, back- and cross-currents are generated which exert a detrimental influence on the course of the treatment. Thus, two or more threads may converge on the smooth guide rollers, and especially on the delivery roller, with the result that filaments of one thread may entangle with those of another thread, thus impeding the fluid treatment. Also, the threads in the interval between the guide rollers may move laterally under the influence of the irregular fluid currents, by which the threads may come into contact with each other and, as a consequence, entanglement of the filaments may occur.

In addition to these and other deficiencies, the entanglement of filaments of adjacent threads is very disadvantageous, because as a general rule it involves rupture of the filaments and the occurrence of loose fibers.

It is therefore an object of this invention to minimize, if not indeed prevent, these objectionable irregular flow characteristics and to prevent counter-current and cross-current flow of the liquid in that portion of the receptacle in which the threads move; and to provide for the uniform and constant flow of liquid in the direction of thread travel. Other objects and advantages of this invention will become apparent as the description proceeds.

According to this invention it has been found possible to prevent said back- and cross-currents as well as the further difficulties arising in the treatment of a great number of threads in a liquid bath by providing a liquid-treating device characterized in that the threads are led over a plate at a distance of some millimeters, e. g., 1-5 mm. from the plate, and in that, at least over part of the plate, the treating liquid moving with the threads over the plate is confined in such manner that the width of the liquid path there is only some millimeters, e. g., 6-14 mm., greater than the width of the path formed by the threads.

The apparatus according to the invention comprises a trough or receptacle having guide rollers at the beginning and end of the receptacle, and an inlet and an outlet for

2

the treating liquid arranged in such a way that the liquid level in the receptacle lies at a distance of some millimeters, e. g., 3-7 mm., above the underside of the guide rollers. In the receptacle a plate is provided having means for keeping the plate at a distance of some millimeters, e. g., 1-5 mm., from the common tangent plane through the undersides of the guide rollers. The sides of at least part of the plate may also be provided with thread guiding edges. It is also desirable to position the plate within the receptacle at such a slope that the threads near the feed roller are at a distance of 1-2 mm. greater from the plate than are the threads near the delivery roller.

Preferably, the length of the plate is such that the plate terminates before the vertical tangent plane at the front side of the delivery roller.

According to another embodiment of the invention, however, the plate extends beyond the delivery roller and there is curved downwardly, this curvature beginning before or at the line intersecting the vertical tangent plane at the front side of the delivery roller. In this embodiment it is advantageous that the curvature be circular and that the radius of the circle be 90 mm.

For a satisfactory flow of the treating liquid it is desirable to round off the ends of the plate in the various types of construction, and a steady flow of the liquid is further promoted if one or more guiding blades are provided in the receptacle near one or both ends of the plate.

In certain instances it is desirable to equip the device with pivoted guide rollers, in which case the means for setting the plate in the trough is additionally adapted so as to allow a downward, temporary displacement of the plates at the ends to insure adequate clearance for the guide rollers as they are swung into operative position about their pivots.

In the device according to the present invention, the plate may be placed in the receptacle in various ways. According to one favorable embodiment the plate is kept in position in the liquid-filled receptacle by means of floating bodies. Preferably, one or more air chambers are then employed as floating bodies.

In order to facilitate the temporary movement of the plate at the ends when pivoted guide rollers are employed, it is desirable to support the plate at the centers of both sides by means of trunnions fitting in the side walls of the trough, so that the plate may revolve about this support.

In any of the various embodiments of the plate, its four corners may be provided, at or near the ends of the plate, with projections extending longitudinally and kept in place against the lower side of the ends of the guide rollers or against plates connected at those points with the rollers.

By way of further illustration of the present invention, it is described hereinafter in conjunction with the accompanying drawings which are to be regarded as illustrative rather than by way of limitation. In the drawings:

Figure 1 shows a top view of one embodiment of the device according to this invention;

Figure 2 shows a vertical sectional view of the device shown in Figure 1, and also swingable or pivoted guide rollers which for simplicity are not shown in Figure 1;

Figure 3 shows a second embodiment of the invention, representing only a part of the trough near the delivery roller;

Figure 4 shows, in the same manner as Figure 3, a third embodiment;

Figure 5 shows, in the same manner as Figure 3, a fourth embodiment;

Figure 6 shows a further improvement of the particular embodiment shown in Figure 5; and

Figure 7 shows a detail of one end of a guide roller useful for keeping the plate in place in the receptacle.

In the several figures 1 denotes an open treating receptacle through which flows the treating liquid 2. The level of the treating liquid is, as indicated in Figure 2, determined by the position of the outlet 3 of the receptacle. The liquid inlet may be accomplished in any conventional manner, not shown.

In the receptacle are located the guide rollers 4 and 5, along the lower sides of which a number of threads 6 (constituting a flat sheet or warp of threads) are led. At a distance of some millimeters apart, the threads, which may number 30, 60, 100, or more, are led through the treating liquid. If no special precautions are taken, there arise in the receptacle due to the draw of the rapidly moving threads in the treating liquid numerous back- and cross-currents which exert an irregular, varying, and detrimental influence under, beside, and over the threads. By providing a plate 7 at a distance of some millimeters under the "bed" formed by the warp of threads 6, a steady flow of the treating liquid is promoted and, especially by limiting the width of the liquid path over the plate by bounding the plate over at least part of its length by means of vertically disposed guiding edges 8, back- and cross-currents are prevented.

As bounding sides, the sides of the receptacle itself may serve as well; in such case care should be taken that the threads are caused to occupy the entire width of the trough to a distance of 3-7 mm. from either side.

Experiments have shown that a steady flow of the treating liquid over the plate 7 is further promoted if the plate is placed in a slightly sloping position, i. e., in such a way that near the feed roller 4 the distance between plate 7 and threads 6 is slightly greater than at the delivery roller 5. This distance need not be more than 1-2 mm. greater than near the delivery roller. The cause of this improvement has not been fully ascertained, though it is considered very likely that the improved effect is based upon a certain levelling in the liquid current as it flows through the receptacle.

In Figures 3, 4, 5 and 6, parts which correspond to parts shown in Figures 1 and 2 are designated by the same numeral with a distinguishing alphabetical suffix. It is understood that the general assembly of Figures 1 and 2 is applicable to Figures 3 to 6, inclusive, which illustrate different types of plates. Figure 3 shows an embodiment in accordance with which the plate 7a is straight over its whole length, and rounded off at the end. Figure 4 shows an embodiment with a similar plate 7b of which the rounded end 20 is thicker than the body of the plate, in order to promote the return flow of liquid under the plate.

In Figures 5 and 6, there are shown plates 7c and 7d the ends of which extend beyond the respective delivery rollers 5c and 5d and are curved downwardly. This curvature of the plates, which is designated at 21 and 22, begins at the line intersecting the vertical tangent plane at the front side of the respective delivery roller.

Experiments with the device according to the present invention have revealed that the further behavior of the liquid current at the end of the plates 7a and 7b, and at the point where the thread runs up the delivery rollers 5a or 5b, is very favorably affected if the plates 7a or 7b be terminated before the vertical tangent plane at the front side of the respective delivery roller. This is also true if the plate is extended beyond the delivery roller 5 and so curved downwardly as at 21 and 22 that the curvature begins before or at the line intersecting the vertical tangent plane at the front side of the delivery roller (see Figs. 5 and 6).

In these particular embodiments of the device according to the present invention, it has been found that a distinct wave-trough is formed in the liquid between the end of the intermediate bottom plate 7a or 7b and the delivery roller 5a or 5b as indicated in Figures 3 and 4,

or beyond the point of curvature of the plate 7c when the end is curved as indicated in Figure 5. The threads do not, or at most they only partly, follow the liquid level when it merges into a wave-trough, probably because the threads are under tension. The result is that each thread floats like a suspension-bridge over the liquid level in the wave-trough proper, whereas a dam-like veil of liquid is formed from each thread in this wave-trough.

These liquid-veils, suspended from the threads, cause a favorable denseness of the threads, with the net result that the filaments adhere less strongly to the delivery roller and show a reduced tendency to float towards adjacent threads so that less loose fibers occur. Moreover, as a result of the suspended liquid dams the threads show a greater stability against lateral shifting and against running in contact with each other on the smooth rollers, and they are less susceptible to displacement by cross-currents in the bath if any should occur. At the same time, the amount of liquid carried from the bath by the threads is strongly affected by the position of the wave-trough with respect to the delivery roller. As a consequence, it has become possible to choose such conditions of operation that the threads carry a minimum amount of liquid, and therefore less liquid flows back from the rising threads, which in turn promotes a more tranquil flow of the liquid.

Owing to the great stability thus effected in the running of the threads through the receptacle 5, it is not necessary for the raised edges such as 8 of the plate 7, see Figure 2, to extend up to the rollers, in particular up to the delivery roller such as 5. This shortening results in that at least a part of the liquid current, induced by the running threads, can immediately flow back laterally into the interspace between the raised edges and the sides of the receptacle, without any harmful effect upon the threads.

It has been found that the best results are obtained when the curvature of the plates 7c or 7d of Figures 5 and 6 is circulated and the circle radius is 90 mm. A very regular flow of liquid is thus effected, especially if a like rounding be also present at the other end of the plate. Further, very desirable results are obtained by providing blades 9 around the ends of plate 7d to guide the liquid along the underside of the plate, and at the other end of the receptacle to return the liquid to the top side of the plate 7d. In Figure 6 only the downward curvature of the plate 7d and the blades 9 at the end of the plate near the delivery roller 5d are shown, it being understood that a similar construction is preferably provided at the thread inlet end of the receptacle. At the liquid inlet side 23 of each set of blades 9 the blades are preferably spaced wider apart than at the outlet side 24.

In case swingable or pivoted guide rollers with auxiliary guide rollers 10 and 11 (see Figure 2) are provided, it is desirable that the means for adjusting the position of the plate in the receptacle be so arranged as to allow of a downward, temporary displacement of the plate and its ends.

The auxiliary rollers 10 and 11 are outside the liquid during normal operation, whilst the rollers 4 and 5 guide the threads through the liquid. The guide rollers 4 and 5 have bearings at the ends of two levers connected at the other ends with the pivots 12 and 13, respectively. Similarly, the auxiliary rollers 10 and 11 have bearings between two levers also connected with the pivots 12 and 13, respectively, and set at an angle with the levers of rollers 4 and 5. When the main guide roller 4 or 5 is swung from the receptacle in the direction of the head side of the receptacle, the auxiliary roller 10 or 11 submerges from the inside into the liquid and takes over the work of guiding the threads. Conversely, resetting each of the levers to its original position brings the main roller into its working position again, and the auxiliary roller is automatically removed from contact with the threads and the liquid.

This thread guiding arrangement has great practical ad-

vantages as the threads are easily "threaded in" and the guide rollers may be cleaned very easily without interruption of the overall process.

With a device constructed according to the invention and having a plate as described above, operating difficulties might be encountered in case swingable or pivoted guide rollers were employed. Swinging the main rollers out or in, and hence respectively the auxiliary rollers in or out of operative contact with the threads, would, without providing also an arrangement permitting a downward, temporary deflection of the plate at the ends as described above, result in that the rollers would come into contact with the plate and the support for the plate.

Consequently, provision is made for the downward, temporary displacement of the plate at the ends in a very simple manner by keeping the plate in position in the liquid-filled receptacle by means of floating bodies. Figure 2 shows the detail of such a floating body, consisting of an air chamber 14 disposed below the flat surface of the plate 7. Thus, the plate in the treating liquid obtains the necessary upward pressure due to the buoyancy created by the air chamber. In addition, in the center of plate 7 trunnions 15 are provided which slide in slots 16 in the sides of the receptacle 1 (see Figure 1), and may revolve or pivot in them. In this way, the plate 7 may move up and down in the liquid, and at the same time, may pivot by means of the trunnions 15 in the slots 16. The ends of the plates thus may be caused to make a downward, temporary movement to provide clearance or additional clearance for the swinging or pivoted guide rollers.

The plate 7 may also be provided with other lifting devices, by which, with the aid of adjusting devices, the distance from the plate to the "bed" formed by the warp of threads undergoing treatment may be adjusted, and which may press the plate upwardly against the rollers. As lifting devices, springs, e. g., tension springs, may be used which press the plate upwards. However, floating bodies and in particular the air chambers described above, have been most satisfactory. Other floating bodies resistant to the treating liquid, e. g. those made of cork, are also serviceable.

In the case of air chambers, these, like the plate itself, may be made of metal, plastic or other suitable material depending upon the nature of the treating liquid.

In order to assist in keeping the plate 7 properly in place, it may be provided at the four corners with extensions 17 (see Figure 1). These extensions or protrusions 17 may rest against bent plates 18 (see Figure 7) mounted near the ends of the pivoted guide rollers. The plates 18 are attached to or supported by the bearings of the guide rollers. In case the guide rollers are not pivoted, a similar construction may be employed at the trunnions by which the guide rollers then are mounted in the sides of the receptacle.

While specific details of preferred embodiments have been set forth above, it will be apparent that many changes and modifications may be made therein without departing from the spirit of the invention. It will therefore be understood that what has been described herein is intended to be illustrative only, and is not intended to limit the scope of the invention.

What is claimed is:

1. Apparatus for the liquid treatment of a warp of moving threads comprising an open receptacle for containing a liquid, thread guiding rollers including a feed roller and a delivery roller disposed in said receptacle and rotatable about horizontal axes, a plate disposed below the normal level of liquid in the receptacle and defining two regions communicating with each other in the upper one of which the warp of threads passes during the liquid treatment, and means for mounting said plate, for vertical adjustment and for tilting about a horizontal

axis parallel to the axes of the thread guiding rollers, and buoyant means in supporting relation to said plate to support the same in the receptacle when the latter is provided with liquid the depth of liquid in said receptacle

5 determining the vertical position of said plate.

2. Apparatus as defined in claim 1 wherein said plate is provided with marginal guiding edges for the warp of threads over at least part of its length.

3. Apparatus as defined in claim 1 wherein said plate 10 is of such a length that it terminates before the vertical tangent plane at the front side of the delivery roller.

4. Apparatus as defined in claim 1 wherein said plate extends beyond the delivery roller.

5. Apparatus as defined in claim 4 wherein the end of 15 said plate curves downwardly beginning near the line of intersection thereof with the vertical tangent plane at the front side of the delivery roller.

6. Apparatus as defined in claim 5 wherein said plate curves downwardly in the form of a circular arc having 20 a radius of approximately 90 mm.

7. Apparatus as defined in claim 1 wherein the ends of said plate are rounded off.

8. Apparatus as defined in claim 7 wherein at least 25 one liquid flow guide blade is located adjacent the rounded ends of said plate, whereby to assist in circulating the treating liquid in said open receptacle.

9. Apparatus as defined in claim 1 in which the means mounting said plate comprises trunnions extending from the center of both sides thereof about which trunnions 30 said plate may revolve, and means defining slots in opposite side walls of said receptacle, said trunnions engaging in said slots in the side walls of said open receptacle.

10. Apparatus as defined in claim 1 wherein said plate is generally rectangular and provided at each of its four 35 corners with longitudinally extending portions that extend beyond and below and cooperate with the lower sides of the thread guiding rollers assembly in order to assist in maintaining said plate at the desired distance below said rollers.

40 11. Apparatus for the liquid treatment of a warp of moving rayon threads comprising an open receptacle for containing a liquid; thread guiding rollers including a feed roller and a delivery roller disposed in said receptacle and rotatable about horizontal axes; a plate disposed

45 below the normal level of liquid in the receptacle and defining two regions communicating with each other in the upper one of which the warp of threads passes during the liquid treatment; means for mounting said plate for vertical adjustment and for tilting about a horizontal axis parallel to the axes of the thread guiding rollers; said plate mounting means including a pneumatic float chamber positioned below said plate in the lower of said regions, the vertical adjustment of said float chamber and plate being determined by the depth of liquid in said

50 receptacle, projecting portions extending from said plate below the guide rollers, means defining slots in opposite side walls of said receptacle and trunnions about which the plate pivots extending from the sides of said plate, said trunnions engaging respectively in said slots; guiding

55 edges extending upwardly from the sides of the plate over at least part of its length and liquid flow-directing baffles adjacent each end of said plate.
